(57) **CLAIM**

The ornamental design for a bottle, as shown and described.

DESCRIPTION

FIG. 1 is a left, front perspective view of a bottle showing my new design;

FIG. 2 is a right, front perspective view thereof;

FIG. 3 is a front view thereof, the rear view being a mirror image;

FIG. 4 is a left side view thereof;

FIG. 5 is a right side view thereof; and,

FIG. 6 is a top view thereof.

The broken lines in the drawings illustrate the portions of the bottle that form no part of the claimed design.
